FREDERICK L. LUCKER, OF BROOKLYN, AND ALLAN O. CARPENTER, OF CORNING, NEW YORK, ASSIGNEES TO INGERSOLL-RAND COMPANY, OF JERSEY CITY, NEW JERSEY, A CORPORATION OF NEW JERSEY.

REGULATING DEVICE FOR MOTOR-DRIVEN COMPRESSORS.

1,169,550.

Specification of Letters Patent.

Patented Jan. 25, 1916.

Application filed December 27, 1912. Serial No. 738,801.

To all whom it may concern:

Be it known that we, FREDERICK L. LUCKER and ALLAN O. CARPENTER, citizens of the United States, residing, respectively, at Brooklyn, in the county of Kings and State of New York, and at Corning, in the county of Steuben and State of New York, have invented a certain new and useful Improvement in Regulating Devices for Motor-Driven Compressors, of which the following is a specification.

This invention relates to regulating devices for compressors and more particularly to regulating devices of the type wherein the motor is cut out at a predetermined maximum receiver pressure and cut in again when the receiver pressure falls to a predetermined minimum and wherein the compressor is unloaded so that the motor can start without difficulty.

In regulators of this type the motor circuit has heretofore been provided with resistance coils which are progressively cut out as the motor speeds up, by purely electrical means. This has necessitated complicated and delicate systems of contacts and wiring which have been at the same time fragile and expensive.

The chief object of the present invention is to eliminate as far as possible electric control of the starting of the motor and to substitute mechanism operated by fluid pressure, preferably from the receiver of the compressor.

A further object is to provide a practical and comparatively simple means for controlling the unloading of the compressor by the same valve mechanism that operates the motor control, and also at the same time to control the cooling water circulation of the compressor.

With these objects in view we have devised a regulating system a practical embodiment of which is shown in the accompanying drawings in which—

Figure 1 shows a diagrammatic view of the whole system and Fig. 2 shows a detail view of one of the resistance controlling switches.

The system as shown in Fig. 1 comprises a compressor 1 driven by a motor 2 and discharging into a receiver 3. Electricity is supplied to the motor through lead wires 4 and 5. Lead wire 5 connects with a series

of switches 6, 7, 8 and 9, here shown as four in number. These switches are arranged to make contact respectively with contact plates 10, 11, 12 and 13 connecting with successive points in a resistance coil or series of coils 14, switch 6 in contact with plate 10 giving the full resistance of the coil 14 in the motor circuit, switches 7 and 8 successively less resistance, and switch 9 giving direct connection with the motor. These switches may be constructed as shown in Fig. 2 and comprise a bell crank lever having a longer arm 15, which is the contact arm, and a shorter arm 16, which is the operating arm, the whole being pivotally mounted on a pin 17, secured in a supporting lug 18. These switches are operated by fluid actuated motors 19, 20, 21 and 22 each of which comprises a cylinder 23 in which slides a piston 24 provided with a connecting rod 25 which is pivotally connected by a pin 26 to the switch operating arm 16. A spring 27 in the cylinder 23 normally keeps the piston 24 at the bottom of the cylinder and holds the switch in open position. To the motors 19, 20, 21 and 22 fluid supply ducts 28, 29, 30 and 31 lead from ports 32, 33, 34 and 35 in a valve chest 36, which is in the form of a cylinder having portions of larger and smaller diameters. Sliding in the valve chest is a valve 37 which consists of two portions, one sliding in the larger diameter part of the valve chest and the other in the smaller diameter part. The larger diameter portion of the valve 37 is in the form of a spool with two heads 38 and 39. The head 39 is provided with a peripheral port 40 which is connected by a transverse passage 41 and longitudinal passage 42 with the valve chest at the farther end of the spool.

From the intermediate part of the larger portion of the valve chest 36 a passage 42 leads to the atmosphere and is in constant communication with the annular chamber formed by the shank of the valve 37. From the larger end of the valve chest a passage 43 leads to a second valve chest 44. Valve chest 44 also has a cylindrical bore of two diameters in which slides a valve 45 having a smaller diameter head 46 and a larger diameter head 47. From the smaller diameter portion of the valve chest 44 a fluid duct 48 leads to the receiver. From the

central part of the valve chest 44 a passage 49 leads to the atmosphere the size of its outlet being controlled by a needle valve 50 adjustably threaded into the valve chest. 5 From the larger diameter end of the valve chest 44 a pipe 51 leads to an auxiliary controlling valve 52. This valve 52 is connected to the receiver by pipes 53 and 54 and its construction forms no part of the present 10 invention being fully described in the co-pending application of W. F. Treiber and E. L. Bulkley, No. 703,644, filed June 14th, 1912. It is sufficient to say here that its construction is such that at a predetermined 15 maximum pressure in the receiver it operates to permit fluid at receiver pressure to enter the pipe 51 and when the receiver pressure falls to a predetermined minimum it opens the pipe 51 to atmosphere through 20 the exhaust opening 55.

Referring again to the valve 37 its smaller diameter portion consists of a rod 56 secured to the head 39, rod 56 having on its outer end a head 57 fitting the smaller diameter 25 portion of the valve chest. From the inner end of the smaller diameter portion a port 58 leads to the atmosphere while from the outer end a pipe 59 leads to a valve 60 which controls the speed of movement of the valve 30 37. This valve 60 comprises a valve chest 61 from the lower end of which a pipe 62 leads to the receiver. Surrounding the opening around the pipe 62 is a beveled valve seat 63 against which seats a check valve 64 which 35 is held to its seat by a spring 65, the air being thus afforded free passage in one direction, that is, from the receiver to the pipe 59 leading into the valve chest 36. A restricted 40 passage for the air in the other direction is provided by a needle valve 66 which seats in a beveled opening 67 in the valve 64 and is adjustably threaded in the valve. From a point in the smaller diameter portion of the 45 valve chest 36 intermediate between the atmospheric port 58 and the inlet pipe 59 a pipe 68 leads to an unloader for the compressor here shown diagrammatically as a valve 69 actuated by a piston 70 to open the discharge line 71 of the compressor to atmosphere when pressure is admitted to the 50 pipe 68. A check valve 71^a prevents the escape of fluid from the receiver 3.

The cylinder of the compressor 1 is surrounded by a water jacket here shown 55 merely as a coil 72 into which water is introduced through an inlet valve 73. This inlet valve is controlled by a piston 74 sliding in a cylinder 75 the piston being moved in one direction to open the valve by a spring 76 and in the other direction by fluid pressure 60 conveyed through the pipe 77 from the auxiliary valve 52.

Referring again to the motor control, one or more of the switches 6, 7, 8 and 9 (here 65 shown only as switch 9) is provided with a

magnetic latch for holding it in closed position. This is shown in Fig. 2 and consists of a latch 78 on the arm 15 which is adapted to be engaged by the hook of a latch bar 79 pivoted near its center on a pin 80. A 70 spring 81 secured to the other end of the latch bar tends to disengage the latch bar from the switch while a magnet 82 is provided to hold it in engagement with the switch while current is passing through the 75 magnet coil. One terminal of the magnet coil is connected to the lead wire 4 while the other is connected to the lead wire 5 through a fluid operated switch 83. This switch consists of a cylinder 84 in which slides a piston 80 85 provided with a rod 86 the upper end of which is secured to the switch bar 87 which is adapted to connect two contacts 88 and 89 connected respectively with the lead wire 5 and with the lead wire 4 through the magnet 82. The piston 85 is held normally in its lowermost position by spring 90, connection thus being made between the contacts 88 and 89 and current passed through the magnet 82, holding the switch 9 in closed position. From the lower end of the cylinder 84 a pipe 91 leads to the auxiliary valve 52 and is adapted to convey fluid under pressure to break the connection between contacts 88 and 89 and deenergize magnet 82 95 releasing the switch 9.

In operation, when the fluid in the receiver reaches a pressure which is determined by the adjustment of the auxiliary valve 52 this valve will operate admitting 100 receiver pressure to the pipe 51. This pipe is connected with the larger diameter portion of the valve chest 44 while the other end of the valve chest 44 is likewise in communication with the receiver through the pipe 48. As the head 47 of the valve 45 is larger than the head 46 the valve will move upwardly. As the head 46 passes the port 48 the valve chest 36 will be disconnected from the receiver pressure in pipe 110 48 and connected to the atmosphere through the port 49. As there is constant receiver pressure in the farther end of the valve chest on the smaller diameter head 57 the valve 37 will move to the left. This will 115 allow receiver pressure to pass into the pipe 68 and open the discharge line valve 69 of the compressor to atmosphere through the action of the receiver pressure on the piston 70. By the operation of auxiliary valve 52 120 fluid under pressure is also admitted under the piston 85 moving it upwardly and breaking the contact connection between the contacts 88 and 89 and hence deenergizing the magnet 82. This allows the spring 81 to 125 release the latch bar 79 from its engagement with the switch 9 and allows the switch 9 to break the motor circuit, cutting out the motor. This movement of the switch 9 is possible since the pipe 31 which 130

serves to convey pressure to the motor 22 to close the switch is open to the atmosphere through the port 42^a, the valve 37 not yet having started to move to the left. By the 5 action of the auxiliary valve 52 fluid under pressure is also admitted to the pipe 77 and passes into cylinder 75 actuating the piston 74 to close the valve 73 which controls the flow of the water through the cooling system 10 72 of the compressor. Thus when the receiver pressure reaches a predetermined maximum, the discharge line of the compressor is unloaded, the motor is cut out and the cooling water cut off. These three 15 regulations take place practically simultaneously.

When by reason of the non-operation of the compressor the receiver pressure has fallen to a minimum determined by the adjustment of the auxiliary valve 52 this valve 20 will operate in the reverse direction and open the pipe 51 to the atmosphere through the discharge outlet 55. This will immediately exhaust the pressure from the cylinder 25 84 and allow the switch 87 again to make connection with the contacts 88 and 89 energizing the magnet 82 and raising the latch bar into operative position. The pressure likewise will be exhausted from the cylinder 30 75 allowing the valve 73 to open and water to flow through the compressor cooling system. The pressure will also be exhausted in the lower part of the valve chest 44 and since there is constant receiver pressure on 35 the head 46 of the valve 43 through the pipe 48 valve 45 will move downwardly its head 46 passing the opening of the passage 43 and allowing receiver pressure to enter the valve chest 36. At this time the valve 37 is 40 at the extreme left of the valve chest 36. The receiver pressure on head 38 will cause the valve 37 to move to the right. This will necessitate the fluid in the other end of the valve chest escaping into the pipe 62 45 through the opening 67 in the valve 63. The rate at which this fluid escapes can be controlled by the adjustable needle valve 66, and hence the speed of the valve 37 as it moves to the right can be regulated 50 as desired. As the valve 37 moves in this direction, as soon as annular port 40 registers with the port 32, fluid will be admitted through the passage 42, 41, 40 into the pipe 28 leading to the motor 19. This 55 will move the piston 24 of this motor upwardly forcing the switch 6 against the contact 10 and connecting in the motor with the full resistance of the coil 14 in its circuit. When the port 40 reaches the port 33 switch 7 will be thrown in like manner cutting out a portion of the resistance in the motor circuit and as the head 39 has passed the port 32 opening it to atmosphere through the port 42^a the 60 switch 6 will drop back into its open posi-

tion after switch 7 has been closed. When the port 40 reaches port 34 switch 8 will be closed in a similar manner. When the port 40 registers with the port 35 the switch 9 will be thrown cutting out all 70 resistance and throwing in the full line current on the motor. As the switch 9 is thrown the catch 78 on its arm 15 will be engaged by the latch bar 79 so that when by the further movement of the valve 37 75 the pressure is exhausted from the motor 22 through the port 42^a the switch 9 will not fall back into its original position but will be held in closed position by the latch until the magnet 82 is again deenergized. 80

It will be observed that the consecutive throwing of switches 6, 7, 8 and 9 takes place without any change in the receiver pressure so that the full current is thrown on to the motor gradually but immediately 85 and it is not necessary for the pressure in the receiver to rise before the motor can be fully loaded.

It is to be understood that the present showing and description discloses only one 90 specified modification of the invention and other forms and modifications are included in the spirit and scope of the invention as expressed in the claims.

What we claim is.

1. In combination, a compressor, its receiver, a motor for driving the compressor, resistance in the motor circuit, a series of switches for progressively varying said resistance, fluid actuated motors for actuating said switches, a fluid operated unloader for said compressor, a controlling valve having portions serving to admit fluid to said switch motors, and to operate said unloader, a magnetic latch to hold one of 100 said switches in closed position to operate said motor, a fluid operated switch controlling said magnetic latch, a fluid actuated water circulation valve, and auxiliary valve mechanism for admitting fluid pressure to 110 operate said controlling valve, said magnetic latch switch, and said water valve, at predetermined receiver pressures.

2. In combination, a compressor, its receiver, a motor for driving the compressor, 115 resistance in the motor circuit, a series of switches for progressively varying said resistance, a magnetic latch for holding one of said switches in closed position to close the motor circuit, fluid operated motors for 120 operating said switches, a fluid operated unloader for said compressor, a valve having a portion serving to progressively admit fluid pressure to said switch motor and a portion serving to operate said unloader, a 125 fluid operated switch for controlling said magnetic latch, and means for supplying fluid to actuate said valve and said latch switch at predetermined receiver pressures.

3. In combination, a compressor, its re- 130

4 ceiver, a motor for driving the compressor, resistance in the motor circuit, a series of switches for progressively varying said resistance, fluid actuated motors for operating said switches, a fluid operated unloader for the compressor, a fluid actuated valve having one portion serving to admit fluid pressure progressively to said switch motors and another portion serving to control said unloader and means to admit fluid pressure to actuate said valve at predetermined receiver pressures.

5 10 15 20 25 30 35 40 45 50 55 60 65 70 75 80 85 90 95 100 105 110 115 120 125 130

4. In combination, a compressor, its receiver, a motor for driving the compressor, resistance in the motor circuit, switch mechanism for cutting in the motor and said resistance, fluid actuated motor mechanism for actuating said switch mechanism, a fluid operated unloader, for the compressor, a fluid actuated controlling valve having one portion serving to supply fluid progressively to said motor mechanism, and another portion serving to operate said unloader, a fluid operated switch for cutting out said motor and auxiliary valve mechanism for actuating said controlling valve and said fluid actuated switch at predetermined receiver pressures.

5. In combination, a compressor, its receiver, a motor for driving the compressor, resistance in the motor circuit, a series of switches for cutting in the motor and decreasing said resistance, fluid actuated motors for operating said switches, fluid ducts to said motors, a valve chest from which said fluid ducts lead, a valve in said chest for serially admitting fluid to said motors, said valve having differential operating areas, means to admit receiver pressure constantly to the smaller operating surface, means operating at predetermined receiver pressures to expose the other surface to receiver pressure to operate the valve, and to the atmosphere to restore it to position, and means to vary the exhaust from the smaller surface to vary the speed of valve movement.

6. In combination, a compressor, its receiver, a motor for driving said compressor, resistance in the motor circuit, a switch for cutting out said motor, an unloader for said compressor, means for operating said switch and unloader at a predetermined maximum receiver pressure switch mechanism for progressively cutting in said motor circuit, fluid actuated motor mechanism for actuating said switch mechanism, said motor mechanism being adapted to operate said switch mechanism from no load to full load at constant pressure, means for admitting fluid to said switch motor mechanism and throwing on said unloader at a predetermined minimum receiver pressure.

65 7. In combination, a compressor, its re-

ceiver, a motor for driving the compressor, resistance in the motor circuit, a series of switches for cutting in the motor and progressively cutting out said resistance, fluid actuated motors for actuating said switches, a fluid actuated sliding valve for successively admitting pressure to said switch motors, means for admitting fluid pressure to actuate said valve at a predetermined minimum receiver pressure, and means to vary the speed of said valve.

8. In combination, a compressor, its receiver, a motor for driving said compressor, resistance in the motor circuit, switch mechanism for progressively varying said resistance, fluid actuated motor mechanism for actuating said switch mechanism, said motor mechanism being adapted to operate said switch mechanism from no load to full load at constant fluid pressure, and means for admitting fluid to said switch motor mechanism at a predetermined pressure in said receiver.

9. In combination, a compressor, a receiver, a motor for driving said compressor, resistance in the motor circuit, a series of switches for progressively varying said resistance, fluid operated motors for actuating said switches, a fluid actuated valve for serially admitting fluid from said receiver to said switch motors, and means for admitting fluid to actuate said valve at a predetermined receiver pressure.

10. In combination, a compressor, a driving motor, resistance in motor circuit, a series of switches for varying said resistance, fluid operated motors for actuating said switches, means for serially introducing motive fluid into, and exhausting said motors, a magnetically controlled latch for locking one of said switches in closed position, and means for releasing said latch at a predetermined fluid pressure.

11. In a fluid operated motor starting mechanism, a motor circuit, resistance in said circuit, a series of switches for progressively cutting out said resistance, fluid motors for closing said switches, pressure operated valve mechanism for serially connecting said motors with a source of fluid pressure, and auxiliary valve mechanism to admit fluid pressure to operate said motor valve mechanism.

12. In a fluid operated motor starting mechanism, a motor circuit, resistance in said circuit, a series of switches for progressively cutting out said resistance, fluid motors for closing said switches, pressure operated valve mechanism for serially connecting said motors with a source of fluid pressure, auxiliary valve mechanism to admit fluid pressure to operate said motor valve mechanism, and means for regulating the speed of said motor valve mechanism.

13. In a fluid operated motor starting

mechanism, a motor circuit, resistance in said circuit, a series of switches for progressively cutting out said resistance, fluid motors for closing said switches, a valve chest, supply ducts for said motors leading from ports in the side of said valve chest, a pressure operated valve sliding in said valve chest for serially connecting said ducts with a supply of fluid pressure, means for regulating the speed of said valve, and valve mechanism for admitting fluid to said valve chest to move said valve.

14. In a fluid operated motor starting mechanism, a motor circuit, resistance in said circuit, a series of switches for progressively cutting out said resistance, fluid motors for closing said switches, pressure operated valve mechanism for serially connecting said motors with a source of fluid pressure and exhausting said motors to atmosphere, and means for holding the last of said switches in operative position.

15. In a fluid operated motor starting mechanism, a motor circuit, resistance in said circuit, a series of switches for progressively cutting out said resistance, fluid motors for closing said switches, pressure operated valve mechanism for serially connecting said motors with a source of fluid pressure, and exhausting said motors to atmosphere, means for controlling the speed of said valve mechanism, auxiliary valve mechanism to admit fluid to operate said motor admission valve mechanism, and means for holding the last of said switches in position after its motor has been exhausted.

In testimony whereof, we have hereunto set our hands.

FREDERICK L. LUCKER.
ALLAN O. CARPENTER.
